UNITED STATES PATENT OFFICE.

HENRY K. McCONNELL, OF RICHMOND, VIRGINIA, ASSIGNOR TO TOBACCO-BY-PRODUCTS AND CHEMICAL CORPORATION, OF LOUISVILLE, KENTUCKY, A CORPORATION OF DELAWARE.

PROCESS AND APPARATUS FOR PRODUCING FREE NICOTINE FROM ITS SALTS.

Application filed August 2, 1922. Serial No. 579,173.

To all whom it may concern:

Be it known that I, HENRY K. McCONNELL, a citizen of the United States, residing at Richmond, county of Henrico, and State of Virginia, have invented certain new and useful Improvements in Processes and Apparatus for Producing Free Nicotine from Its Salts, fully described and represented in the following specification and the accompanying drawings, forming a part of the same.

The present invention relates to an improved process for producing free nicotine from its salts.

15 The object of the invention is to provide a commercial process for large scale operation whereby strong solutions of free-nicotine may be obtained from solutions of nicotine salts at a low labor cost.

20 With this general object in view, the process consists in mixing an aqueous solution of a nicotine salt with hydrated lime, subjecting the mixture to dry heat (which, it has been discovered, may be at a temperature relatively high as compared with the temperatures heretofore considered permissible with nicotine or its compounds), while at the same time protecting the materials, including the vapors, from access 25 of air, and leading off and condensing the vapors evolved from the mixture by the heat.

25 For the purpose of carrying out the process conveniently on a commercial scale, a new apparatus has been devised which, however, forms no part of the present invention.

This new apparatus comprises a plurality of receptacles closed against admission of air, one, the retort or still, being heated by 40 a suitable source of heat, the second serving as a condenser, and the third serving as a receiver for the condensed aqueous solution of nicotine. The process is carried out as a batch operation, but the apparatus is 45 so constructed that the still may be quickly emptied of its spent materials and a new charge supplied, while the receiver may be emptied from time to time, so that the operations may be carried out in rapid succession.

In the best form of the apparatus, there

is an air pump in connection with the receiver at a point above the highest level to which the condensate accumulates in the receiver. The air pump serves to draw off 55 the air from the apparatus and, of course, to reduce the pressure within the apparatus. In practice I have found that a reduction of the pressure to about 24 or 25 inches of mercury is all that is necessary. 60

The invention will be more specifically described in connection with the accompanying drawings, in which,—

Fig. 1 is a diagrammatic view of an apparatus particularly suitable for carrying 65 out the invention.

Fig. 2 is a sectional view through one of the stills.

Referring to the drawings, 1 is the still, 70 2 the condenser, 3 the receiver for the condensate, and 4 the air-pump arranged to be operated by any suitable means, as, for example, an electric motor, not shown.

The still 1 is suitably supported in a furnace, the walls of which are indicated 75 at 5, and is heated below in any suitable way, as, for example, by gas burners as indicated at 6, Fig. 2. The individual burners are controlled by valves 7 and the gas main 8 is controlled by a main valve 9. 80

The still is of any suitable shape, but in the construction which has heretofore been employed by me with good results, the bottom is flat and the top arched. The still heads are bolted in place on the flanged 85 ends of the body of the still, as will be clear from the drawings. A suitable packing is employed between the contacting surfaces of the heads and flanges so as to prevent leakage of air, and in order to maintain these air-tight joints, the ends of the still are allowed to project beyond the furnace so that they will be air-cooled. 90

The head at one end of the still is provided with an opening through which spent material may be removed from the still, this opening being closed by a removable closure device. In the present example, the hole is circular and is tapped to receive a screw-threaded plug 10 having a polygonal 100 head to which a wrench may be applied.

The still is provided with suitable means

for charging it. In the present example, this means consists of a filling pipe 11 provided with a valve 12 and extending from the top of the still toward the bottom of the floor. A receptacle 13, filled with the new charge, may be placed at the lower end of the filling pipe and elevated so that the said pipe will enter the receptacle. When the valve 12 is opened while the air-pump is in operation, the new charge will be driven by the exterior atmosphere into the still 1, whereupon the valve 12 is closed.

The still 1 is connected with the condenser 2 by a pipe 14. The condenser 2 is cooled in any suitable way, as, for example, by locating it in a tank 15 supplied with cooling water by a water-inlet pipe 16, a suitable water overflow pipe 17 also being provided.

20 The bottom of the condenser 2 is connected with the receiver 3 by a pipe 18. The air pump 4 is connected to the receiver by a pipe 19. The receiver may be emptied by a discharge pipe 20 having a valve 21.

25 In carrying out the process, a suitable aqueous solution of a nicotine salt is used as the starting material. In practice the nicotine sulphate or chloride is usually employed, and generally it is advantageous to use a concentrated solution.

30 The solution of nicotine salt is thoroughly mixed with hydrated lime, which, of course, is a fine powder. It is important to use freshly hydrated lime, because old material has an appreciable amount of carbonate of lime, which is disadvantageous.

35 The mixture of hydrated lime and nicotine salt solution should be made in the proportion of 1.5 parts by weight of lime to 10 parts by weight of nicotine solution of 40% strength, although these proportions may be varied somewhat in practice without materially affecting the results.

40 The mixture, which is a thick fluid mass, may then be charged into a retort or still so as to form a layer of considerable depth therein. The still is in connection with a suitable condenser preferably water-cooled. Air is removed from the still and condenser 45 in any suitable way, as by injecting an inert gas, for example, nitrogen, or by blowing out the air with sufficient steam, whereupon the steam is cut off. Preferably, however, the air is removed with an air-pump.

50 The still is then heated externally to give a temperature of the vapors of about 400 to 500° F. It has been found that this can be done without injury to the product. This is contradictory to the previous view

55 in the art that nicotine compounds and particularly free nicotine would be decomposed at such high temperatures. In fact, in carrying out my process in the apparatus heretofore described, I have carried the temperature as high as 900° F. in the vapor

line without injury to the free nicotine but in practice, it is unnecessary to go so high, and the temperature range of 400 to 500° F. will be all that is necessary for rapid evolution of the free nicotine. The heating is maintained until all of the free nicotine is driven off. When carrying out the process in an apparatus such as hereinbefore described with a still having an interior length of 30 inches and width of 24 inches and with a charge of 243 pounds comprising 32 pounds of hydrated lime and 211 pounds of a 40% aqueous solution of nicotine sulphate, I have found that substantially all the free nicotine will be evolved in about 13 hours, if the retort or still be maintained at a temperature of about 400 to 500° F.

60 The new process has many important advantages over the processes heretofore employed for obtaining free nicotine.

65 One important advantage over prior processes using steam for driving off the free nicotine is that the solution obtained by me is at least as strong as the solution of the nicotine salt used in starting, because no additional water-vapor is introduced during distillation. In fact, in practice, the solution of free nicotine obtained by my process is somewhat more concentrated than the solution of nicotine salt, because some of the water vapor is not condensed with the nicotine solution.

70 A further important advantage is a greater efficiency of operation. Prior processes have shown as their best results a recovery of about 83% of the nicotine in the starting solution. My new process in every day operation has given a recovery of 95% even at a low temperature of about 350° F. and as high as 98% recovery at the temperatures 75 of 400 to 500° F.

75 Still another great advantage of the process is that it is relatively rapid because at the higher temperatures the free nicotine 80 goes off more rapidly. This permits a greater output with a more compact apparatus and with a lower labor charge per unit of free nicotine. The more compact apparatus of course reduces the investment 85 charge. For these reasons, the total cost of production of free nicotine is materially reduced.

85 What I claim is:

1. The process of obtaining free nicotine 90 from solutions of its salts, which consists in mixing hydrated lime with an aqueous solution of a nicotine salt, subjecting the mixture to dry heat while excluding the air from it, and carrying off and condensing the 95 vapors.

2. The process of obtaining free nicotine, which consists in preparing a mixture of hydrated lime and an aqueous solution of a nicotine salt, subjecting the mixture to a dry 100

heat while under a pressure less than atmospheric, and carrying off and condensing the vapors.

3. The process of obtaining free nicotine, which consists in preparing a mixture of hydrated lime and an aqueous solution of nicotine salt in the proportion of about 1.5 pounds of lime to 10 pounds of nicotine in

said solution, subjecting the mixture to a temperature of about 400-500° F. under a pressure of about 24 to 25 inches of mercury, conducting off the vapors and condensing them.

In testimony whereof, I have hereunto set my hand.

HENRY K. McCONNELL
